SOLVENT EMULSION CLEANER

Charles S. Lowe, Upper Darby, Pa., assignor to
The Pennsylvania Salt Manufacturing Com-
pany, Philadelphia, Pa., a corporation of Penn-
sylvania

No Drawing. Application November 19, 1943,
Serial No. 510,975

6 Claims. (Cl. 252—118)

This invention relates to a concentrate type solvent emulsion cleaner.

An object of the invention is to provide a solvent emulsion cleaner composition which may be diluted with a hydrocarbon, a chlorinated hydrocarbon, or equivalent solvent, following which it may be applied directly to a soiled article, from which it can be removed with water, thereby cleaning said article.

Other objects and advantages will be apparent from a study of this specification and the claims.

My invention is predicated upon the selection of the ingredients and upon the manner and proportions in which these are compounded.

A solvent emulsion cleaner prepared according to the invention will contain the following ingredients in the recited proportions by weight:

Refined talloel	46.2
Triethanolamine	8.8
Potash, 50% (49.2 Bé)	23.5
Ethylene glycol mono butyl ether	14.2
Pine oil (specific gravity 15.5/15.5° C.)	7.3
0.9398	
Total	100.0

The composition of the invention is prepared by adding the refined talloel to the triethanolamine, preferably through a spray, and the resulting amine soap is thoroughly mixed for at least 5 minutes or until the reaction is complete. The pine oil and the ethylene glycol mono butyl ether are then introduced by slow pouring or spraying during continued stirring. The potash solution is then added by spraying and mixing is continued for twenty to thirty minutes or until the heat liberated by the reaction has been dissipated. The heat liberated is generated through reaction of the potash with the talloel uncombined with the triethanolamine and by the displacement of triethanolamine from the soap formed, leaving all the triethanolamine in free form and a potash soap of talloel.

The composition thus prepared is a liquid, and before application to the article to be cleaned, it is preferably diluted with a hydrocarbon, a chlorinated hydrocarbon, or equivalent solvent, such as kerosene or a chlorinated benzene.

The quantity of kerosene employed to dilute the composition can be varied and up to one part solvent emulsion to fifteen parts kerosene has shown no evidence of settling on standing for over forty-eight hours. One part of solvent emulsion to twenty parts kerosene will show a slight haze and will give a slight amount of set-

tling on standing, but this is in no way detrimental to its cleaning efficiency. The stability of the diluted solvent emulsion is characteristic of my invention, no other solvent emulsion cleaner being known which can be diluted fifteen to twenty times with kerosene without undergoing rapid settling of the active ingredients.

As stated, instead of a simple hydrocarbon, such as kerosene, a chlorinated hydrocarbon may be employed, for example, ortho-dichlorobenzene.

The selection of the ingredients and the proportions employed in the composition of a solvent emulsion cleaner, according to the invention, is important and the presence of each ingredient in the proper proportions is critical to the obtaining of desired results.

It is possible, however, to employ, in place of the caustic potash, equivalents such as caustic soda, soda ash, ammonia and the like and to obtain a desirable result. Obviously, varying proportions of combinations of these ingredients may be employed as long as the total alkalinity is equivalent to that herein stated. Caustic potash seems, however, to be preferable. The presence of free caustic potash in the final composition plays an important part in the cleaning effect produced, saponifying reactive oils and greases to render these water soluble. The quantity of potash employed is such that there is more than enough to react with all of the talloel so that there is actually present free potash.

The presence of free amine in the final composition also plays an important part in the stability of the emulsion and the cleaning effect produced therewith. In place of triethanolamine, there may be employed amines, ethylene diamine, monoethylamine, diethylamine, morpholine, amines formed from nitroparaffins, butylamine, di-2-ethylhexylamine, tetraethylenepentamine, propylenediamine, and diethylethanolamine.

The presence of both the amine and the potash or equivalent alkali, in the composition is necessary. In other words, although the amine is alkaline in character and capable of forming soap with the talloel, it is necessary that an inorganic base also be present in order to obtain a satisfactory emulsion concentrate. Without the amine in the composition, even though additional potash is employed, the results obtained according to this invention cannot be accomplished.

Talloel employed in the composition of this invention is a saponifiable by-product from kraft pulp manufacture and is rich in both rosin acids and fatty acids of complex character. As an ex-

ample, a suitable talloel will have the following characteristics:

Acid number	170-180
Saponification number	170-185
Rosin acids as abietic	per cent 34-38
Fatty acids	do 50-60
Sterols, higher alcohols, etc.	do 6-10

A talloel of substantially the characteristics given will yield a final composition which can be diluted up to one part of solvent emulsion to 15 parts kerosene without settling over a 48-hour period and while some variation from the values given is possible, it is preferred to remain within the ranges stated. In place of some or all of the talloel there may be employed castor oil, cotton-seed oil, linseed oil, palm oil or even sulfonated oils and in such cases of substitution it may be necessary to vary somewhat the quantity of the particular oil employed in place of the talloel.

The pine oil in the presence of the other ingredients of the composition of the invention seems to promote the extendibility of the solvent emulsion concentrate. In other words, it is possible to dilute with large quantities of kerosene, as aforesaid, without settling of the active ingredients. While the combination of the several ingredients as outlined is essential for good cleaning and stability, it is possible to substitute for some or all of the pine oil phenolic type compounds such as cresylic acids, phenol, ortho, meta, and para cresols, hydrogenated phenol, and alcohols, such as methanol and isopropanol.

The ethylene glycol mono butyl ether acts as an emulsion stabilizing ingredient and while essential to the composition, it may be partly or totally replaced by equivalents such as diethylene glycol mono butyl ether, diethylene glycol monoethyl ether or diethylene glycol mono methyl ether.

If pine oil, or its equivalent, is omitted from the composition, it is not possible to obtain the high hydrocarbon dilutions, referred to herein without settling of soap from the emulsion and if the ethylene glycol monobutyl ether, or its equivalent, is omitted, there is little or no emulsification of hydrocarbon solvent in water.

The methods of application of solvent emulsion cleaners are known. The preferred method of application, according to the invention, is that wherein the soiled article is dipped, sprayed, or otherwise contacted with the product, before or after dilution with kerosene, but before forming the water emulsion. For example, the composition, after a suitable quantity of kerosene has been admixed, is applied to the soiled article, and, after remaining in contact therewith for from one to five minutes, the article is washed with water by rinsing or hosing or the like. In general, pressure hosing is preferred. The surface to be cleaned should preferably be dry so that a water emulsion is not formed when the liquid cleaning composition is first applied. It is within the scope of the invention to rinse with a dilute alkaline solution, in the place of water.

Another known method of employing the composition of this invention is that wherein the emulsion in water is first formed before contacting the work or article to be cleaned. The work may then be soaked or the emulsion may be made up in a power washer and sprayed over the work. In such operation, temperatures up to 160° F. have been satisfactorily employed. The emulsions may be made up in dilute alkaline solutions,

in the place of water, thus obtaining both the effect of the alkali reaction and the dissolving reaction of the grease solvent. In general, the more concentrated the water emulsion, the better the cleaning will be and the preferred range is one part of kerosene diluted composition, in twenty-five parts to one hundred parts of water or alkaline solution.

The solvent emulsion cleaners and the water, or alkaline solution emulsions prepared therewith, are applicable to the cleaning of metal objects to loosen and remove solid dirt particles such as very fine particles of carbon smut, firmly imbedded in a matrix of grease and oil. These solvent emulsion cleaners are also applicable to cleaning of painted surfaces and also to the cleaning of heavily soiled laundry. Generally, a cleaner prepared according to this invention will be found applicable to the removal of heavily and deeply imbedded soil from almost any type of material or article.

The proportions indicated in the formula first given are now thought to be those which yield the best results, but it will be obvious to those skilled in the art that compositions prepared according to a somewhat different formula will possess the advantages of the invention, the invention comprising not only the relative quantities of ingredients employed in preparing the composition but also the combination of the specific ingredients. A composition employing ingredient proportions within the following ranges will yield satisfactory results:

Parts by weight		
35 Refined talloel	40-60	
Triethanolamine	7.6-11.4	
Potash, 50% (49.2 Bé.)	20-30	
Ethylene glycol mono butyl ether	12-18	
Pine oil (specific gravity 15.5/15.5° C.)		6.4-9.6
40 0.9398)		

I claim:

1. A solvent emulsion cleaner composition comprising a mixture in parts by weight of 40 to 60 of talloel; 7.6 to 11.4 of triethanolamine; 20 to 30 of 50% potash solution; 12 to 18 of ethylene glycol mono butyl ether; 6.4 to 9.6 of pine oil, the parts by weight of potash being so selected that it will be present in excess after reacting with all of the talloel in the composition.

2. A solvent emulsion cleaning solution comprising the composition of claim 1 diluted with from one part to twenty parts by weight of kerosene.

3. A solvent emulsion cleaning solution comprising the composition of claim 1 diluted with from one part to twenty parts by weight of a chlorinated benzene.

4. A solvent emulsion cleaning solution comprising the composition of claim 1 diluted with from one part to twenty parts by weight of ortho dichlorobenzene.

5. A solvent emulsion cleaning solution comprising the composition of claim 1 diluted with from one part to twenty parts by weight of kerosene and with from twenty-five parts to one hundred parts by weight of water.

6. A solvent emulsion cleaner composition comprising a mixture in parts by weight of refined talloel 46.2 parts; triethanolamine 8.8 parts; potash, 50% (49.2 Bé.) 23.5 parts; ethylene glycol monobutyl ether 14.2; and pine oil (specific gravity 15.5/15.5° C. 0.9398) 7.3 parts.

CHARLES S. LOWE.
